UNITED STATES PATENT OFFICE.

PETER E. WIBERG, OF GLEN RIDGE, NEW JERSEY.

DESIGN FOR A COLLAR-CLASP OR SIMILAR ARTICLE.

58,123.

Specification for Design.

Patented June 7, 1921.

Application filed November 26, 1920. Serial No. 426,652. Term of patent 14 years.

To all whom it may concern:

Be it known that I, PETER E. WIBERG, a citizen of the United States of America, and a resident of Glen Ridge, in the county of Essex and State of New Jersey, have invented a certain new, original, and ornamental Design for Collar-Clasps or Similar Articles, of which the following is a specification, reference being had to the accompanying drawing, in which—

Figure 1 is a side elevation of a collar clasp showing my new design;

Fig. 2 is a bottom plan view of the collar clasp showing my new design.

I claim:

The ornamental design for a collar clasp or similar article, as shown.

Signed at Glen Ridge in the county of Essex, State of New Jersey, this 29th day of October, 1920.

PETER E. WIBERG.
